UNITED STATES PATENT OFFICE.

CHRISTOPHER DELP, OF OAKLAND, CALIFORNIA.

OIL CAN.

Application filed March 24, 1928. Serial No. 264,333.

The invention forming the subject matter of this application relates to oil cans.

The primary object of the invention is the provision of an oil can constructed of two complementary sections having resilient side walls and a spout of such a construction as to permit the ready flow of oil from the can without tilting the same, when the same is properly manipulated, at the same time effecting the admission of air into the can when the pressure on the resilient walls is released.

With the above mentioned objects and other objects in view, the invention consists in the novel construction and combination of parts hereinafter described, illustrated in the accompanying drawings, and set forth in the claim hereto appended, it being understood that mere changes in the form, size, proportion, and minor details of construction within the scope of the claim may be resorted to without departing from the spirit of or without sacrificing any of the advantages of the invention.

For a full understanding of the invention, reference is to be had to the following description and accompanying drawings in which:

Figure 1 is a side elevation of the improved oil can;

Figure 2 is a sectional view taken on the line 2—2 of Figure 1; and

Figure 3 is a modified form of the oil can.

In carrying out my invention, I make use of two complementary can sections, denoted by the numerals 6 and 7. The open end of the section 6 is flared sufficiently to receive the end of the other section 7 therein. The two sections are assembled in the manner shown in Figure 2 and then secured to each other by means of solder, which also seals the joint. On the top of each section is a semi-circular cut out portion, designated by the numeral 9 for forming an opening when the two sections are soldered to each other, so that the cut out portions complement each other. The side of each section is formed with a centrally disposed spring plate 11. After the two sections are soldered together, a neck 12 is soldered above the opening 10, said neck being corrugated so as to form a thread in which is screwed a correspondingly threaded cap 13.

A spout 14 extends into the oil can thru a hole at said sealed joint and is disposed in the inclined position shown in Figure 1. The lower end 16 of the spout 14 is cut at an angle to the incline of the spout and to the bottom

of the can. The upper end of the spout 14 is reduced and turned outwardly so that it may be readily applied to the parts which are to be oiled. It is to be noted that the spout 14 is gradually tapered, the larger end thereof being the end 16, adjacent to the bottom of the can, and then it tapers down to a comparatively small opening at the end of the upper curve 17.

In order to further increase the resiliency of the spring plates 11, a spring 18 is inserted in such a position as to press against the center of the plates 11, thereby rendering the operation of the plates more positive, one end of the spring being secured to one of the plates 11.

After the can is filled with oil and the cap 13 is screwed thereon, it is evident that the spout 14 functions as an airvent. When the plates 11 are compressed against the action of the spring 18, then the oil is forced out of the can thru the spout 14 which will function similarly to a nozzle on account of the gradually decreasing cross sectional area thereof. After the spring plates are released and returned to the original position, the suction created thereby will draw air thru the spout 14, in which spout there is trapped a certain amount of air. At the same time, the withdrawal of the oil from the spout by said suction will also carry a certain amount of air therewith to produce the atmospheric pressure in the can. The air bubbles thru from the opening 16 to the top of the can above the oil level and fills up the vacuum created by the expelling of the oil from the oil can.

The modified form shown in Figure 3 is an oil can of similar structure to that of the can heretofore described, excepting for the circular shape of the side thereof, instead of the rectangular shape shown in Figure 1.

It will be recognized that an efficient oil can is provided in which the use of an airvent may be entirely eliminated because of the air entering thru the particular shape and construction of the spout 14. The oil can is readily operated by compressing the resilient sides thereof, thus producing an almost continuous flow thru the spout without tilting the can.

I claim:

An oil can of the character described comprising two complementary sections secured to each other so as to form the body of the can, resilient diaphragms in the opposite

faces of the body; an outlet spout extending thru the side of said body near the top thereof, the spout being tapered so as to uniformly increase in diameter toward the bottom and

⁵ being slightly tilted, the lowermost end of said spout being cut away at an angle to the bottom of said body, said sections having

complementary openings in the top thereof so as to form an inlet opening when assembled, and means for covering said inlet opening.

In testimony whereof I affix my signature.

CHRISTOPHER DELP.
